Technical drawing of a three-tiered structure, labeled 'Fig. 3.' at the top. The structure consists of three parallel horizontal layers, each with a series of vertical slats or bars. The top two layers are labeled '8a' and the bottom layer is labeled 'A'. The drawing shows a perspective view of the structure, with the top layer receding towards the right. The labels are placed near the left edge of each layer. The entire structure is rendered with fine lines and cross-hatching to indicate depth and texture.

UNITED STATES PATENT OFFICE.

WILLIAM LEWIS EVANS, JR., OF WASHINGTON, INDIANA.

BUILDING CONSTRUCTION.

Application filed July 27, 1921. Serial No. 487,919.

To all whom it may concern:

Be it known that I, WILLIAM L. EVANS, Jr., a citizen of the United States, residing at Washington, in the county of Daviess 5 and State of Indiana, have invented new and useful Improvements in Building Con- structions, of which the following is a speci- fication.

This invention has reference to building 10 construction, and its object is to provide a construction utilizing concrete or some sim- ilar cementitious material as the filling-in material, with metal facings or skins serv- ing as forms and which become a perma- 15 nent part of the wall, floor, ceiling or col- umn entering into the building construc- 20 tion, which is of a nature permitting rapid assembly without those delays incident to the drying out or hardening of the filling-in material, and permitting, particularly in 25 walls, of the completion of the forms to the full height contemplated before the filling-in material is poured.

The invention has the advantage of ex- 30 tremely economical construction, since the outer walls, which also constitute the forms may be made of cheap sheet metal of suit- 35 able gage, sheet iron answering the purpose, as sheet iron is susceptible of protection against rust or deterioration by various treatments, of which sherardizing may be taken as an example. This is a process of 40 treating the iron in a receptacle with powdered zinc and heating the materials to a temperature a little less than the melting 45 point of the zinc, whereby the zinc is caused to enter the pores of the iron and combines with it into an alloy to produce the pro- 50 tecting coating.

In preparing the metallic skin to produce 55 the outer or mold surfaces, which may be both inner and outer surfaces in the case of a wall or the receptacle for the filling-in material, in the case of a floor or a ceiling, or the sides in the case of a column, trough- 60 like elements are provided, consisting of suitably elongated sheets of metal of appro- priate gage, with the long edges bent at an angle to constitute flanges, the troughs 65 being assembled into any desirable area with adjacent flanges in contact and riveted or otherwise secured together, while the op- 70 posite faces, in the case of an upright wall are joined at appropriate intervals by 75 spacer strips or tie rods determining the

thickness of the completed wall, which is ultimately filled with concrete or the like 80 poured between the joined walls and al- lowed to set. In cheaper constructions and where conditions permit, clay may be sub- 85 stituted for concrete, but, without limiting the invention to the use of concrete, it will hereinafter be considered that the filling 90 material for the wall or other structure is concrete of suitable composition.

The trough-like structures are joined in 95 edge to edge contact into suitably extended areas by fastening means connecting the flanges engaged in face-to-face engagement, the metal of the flanges being punched 100 through in a manner to provide matching 105 passages with raw edges, the punching re- sulting in the extension of these raw edges beyond one face of the joined flanges, and then returned or upset against that face 110 of the flanges from which they project, after which the projecting edges are upset 115 in a manner to anchor the adjacent flanges together. The perforations thus produced 120 are made to match throughout the length 125 of the construction to provide for the passage of reinforcing rods, but the per- 130 forations are also made of relatively large 135 size with respect to the rods so that the latter may lie close to one side of the 140 perforations, providing ample room about 145 the rod for the spontaneous flow of the con- 150 crete through the holes made in the flanges 155 to produce anchoring junctions through the 160 flanges from one trough-like member to the 165 next in order.

In this manner the concrete filling is to 170 an extent monolithic. Instead of securing 175 the flanges of the adjacent troughs or skin 180 elements together, by punching holes there- 185 through with ragged edges and upsetting 190 and riveting them together after the man- 195 nner of tubular rivets, the holes may be 200 smooth holes, but matching to pass rein- 205 forcing rods and bolts, may be employed to 210 fasten the troughs together. Furthermore, 215 the plane faces of the troughs between the 220 flanges may be strengthened and stiffened 225 by lateral corrugations which, in conjunc- 230 tion with the reinforcing rods and tie or 235 spacer bars, impart particular rigidity and 240 resistance to collapse of the metallic skins 245 containing the concrete filling.

The invention will be best understood 250 from a consideration of the following de- 255

tailed description taken in connection with the accompanying drawings forming part of this specification, with the understanding, however, that the invention is not confined to any strict conformity with the showing of the drawings, but may be changed and modified so long as such changes and modifications mark no material departure from the salient features 10 of the invention as expressed in the appended claims.

In the drawings:

Figure 1 is a perspective view, partly completely and partly broken away and in 15 section, of an upright wall embodying the invention.

Figure 2 is a plan view of the structure shown in Figure 1.

Figure 3 is a partly complete and partly 20 incomplete perspective view of a floor structure embodying the invention.

Figure 4 is a similar view of a floor structure somewhat modified from the arrangement of Figure 3.

Figure 5 is an upright section in the line 25 of the reinforcing rods, and showing a small portion of a completed part of a floor section, formed after the plan of Figure 3.

Figure 6 is a similar view but following 30 the construction of Figure 4.

Figure 7 is an upright section showing two sides of a corner in an upright wall, similar to the arrangement of Figure 1.

Figure 8 is a vertical section of an upright 35 wall and a cross section of a ceiling embodying feature of the invention.

Figure 9 is a detail cross section of a portion of ceiling shown in Figure 8.

Figure 10 is a view similar to Figure 9 40 but showing a modified form of the ceiling structure.

Figure 11 is a perspective view of a portion of the structure shown in Figures 8 and 9 but with the plaster omitted.

Referring to the drawings, there is shown 45 in Figures 1, 2 and 7, an upright wall construction in which there are inner and outer skins A and B. Each skin or surface A and B is made up of numerous trough-like 50 box-like sections 1, simulating wall blocks, each composed of an elongated strip of metal of suitable width and also of appropriate gage, terminating at the long edges in inturned flanges 2 which may be perpendicular to the plane of the trough-like 55 structure 1, so that the flanges may be brought into face-to-face contact, with the two meeting flanges constituting a reinforcement lodged within the space between 60 the two outer skins of the wall. In order to determine the thickness of the completed wall, the flanges 2 on opposite faces thereof, are secured together in spaced relation by appropriate bars 3, each bar being riveted, 65 pinned, or bolted to the flanges with which

it is connected. The flanges are provided with openings and the bars or tie rods have bolts or rivets which engage said openings and connect and hold the skins or sections together.

Each pair of flanges 2 has matching perforations or passages 4, and these pairs of perforations also align throughout the extent of the wall to pass reinforcing rods 5 located between the trough-like facings 75 of the wall and initially upheld by the flanges 2 at the bottoms of the perforations by which the rods are supported.

The perforations 4 are produced at frequent intervals so that an appropriate number of reinforcing rods 5 may be utilized, but the spacing bars 3 may be less numerous and are utilized to receive and sustain other reinforcing bars 6 located intermediately 80 of the space between the skins A and B.

The reinforcing rods 5 extend in superposed order sufficiently close to the skins or facings A and B to pass through the perforations 4, while the intervening space between the inner and outer walls or skins 85 A and B may contain the reinforcing bars 6 in superposed order and about intermediate of the thickness of the wall, although this particular arrangement is not at all obligatory.

In order to fasten the trough-like sections or elements of the upright wall together, in the showing of Figures 4 and 8, short bolts 7 are made to traverse the flanges 2, thereby joining the trough-like 100 elements together.

After the metallic facings or skins are assembled, and this operation may be continued through the extent of the structure, a suitable concrete mixture C is poured into 105 the space between the walls defined by the facings A, B, embedding the rods 5, bars 6, joined reinforcing flanges 2, and bars 3, flowing through the perforations 4 to both sides of the flanges 2 so that when the concrete has set, the various parts embedded by the concrete are anchored in a practically monolithic mass of concrete. In this manner the metallic part of the wall becomes effectively joined at frequent intervals 110 whereby the skin is so united as to distribute to the whole structure the strains due to contraction and expansion of the metal, confining such strains to small areas, while the metal and concrete become securely bound together.

In order to stiffen the relatively thin facings or skins to withstand outward pressure caused by the weight of the concrete before it has set, the plane parts of the 115 trough-like members A and B between the flanges 2 are provided with corrugations 8 extending lengthwise of the wall and suitably spaced one above the other. These corrugations may be rolled or otherwise pre- 120

duced in the sheet metal out of which the walls are built.

In case of an angle in the continuity of the wall, say a right angle, as in Figures 5 1 and 2, right angle flanges 2 occur on opposite sides of the skins or facings of one member of the completed wall, while in the other completed wall joining the first wall at an angle, the flanges 2 are in 10 alignment therewith so as to provide aligned extensions 2^a secured to the respective flanges 2 by bolts or rivets or other suitable fastening devices 7^a.

The construction already described is susceptible to employment not only for upright walls, but for the production of floors or 15 ceilings. In Figures 4 and 6, the trough-like elements are horizontal, or approximately so, and in Figure 4, trough-like elements A have upstanding flanges 2 with smooth matching perforations 4 through which reinforcing rods 5 project, and the flanges are secured together by bolts 7. The rods 5 naturally gravitate to the bottoms of the holes or perforations 4, and when concrete is filled into the trough-like 25 members 1, the rods 5 become embedded and, on the hardening of the concrete, the floor material confined in the troughs assumes a monolithic character with integral 30 anchors of concrete through the passages 4.

In the structure shown in Figures 3 and 5, a somewhat different construction is illustrated. The meeting flanges 2 have the 35 edges remote from the plate-like bases of the trough-like elements each formed with a return bead 8^a with one return bead housing the other one, whereby to interlock the otherwise free long edges of the 40 flanges, besides greatly stiffening the reinforcing quality imparted to these flanges. Furthermore, matching perforations 4^a are punched through the contacting flanges so that there is a raw edge or burr 9 formed 45 about the raw edge of the perforation 4^a and the burr is turned back against the face of the flange through which it projects, after the manner of the tubular rivet, thereby securing the two flanges solidly 50 together, this being shown particularly in Figure 5 and indicated in Figure 3. The reinforcing quality of the flanges 2 in the structure shown in Figures 3 and 4 is greatly increased and the metal skin or facing of 55 the completed structure is greatly strengthened.

This invention is an improvement upon the building construction illustrated and described in my application No. 466,843, filed May 4th, 1921, in which one face of the wall is made up of a single-thick layer of brick, with a removable molding form temporarily secured thereto in spaced relation thereto so that the concrete is poured 60 between the permanent brick wall and the

temporary mold face to complete the wall. For certain classes of work, this construction is very desirable, although it has some disadvantages. The cost of the brick and the cost of laying them represents a high 70 initial cost. Moreover, it is difficult to get brick masons sufficiently skilled to lay up the brick with water-tight joints, or even to get brick masons in sufficient numbers and at prices which will justify the laying 75 of the brick. Furthermore, the brick, after being laid, must stand long enough for the mortar to set before the forms can be put into place and the concrete poured.

In accordance with the present invention, 80 the skin employed not only acts as a form for the concrete wall, but also as a permanent skin or facing for the building, and is cheap in first cost and easy of construction. It will also permit the work to go forward 85 as soon as the skin is put in place, and without having to wait for the drying of mortar. Furthermore, such a skin is impervious to moisture and can constitute both the outside and inside of the wall so that 90 the latter may be completed as soon as the concrete is poured.

Since there are several known processes 95 of rendering sheet iron rust-proof, the skin construction may be set up very cheaply and may constitute a permanent part of the wall, thus necessitating no false work to be subsequently torn down.

In producing an upright wall or partition, which it is desired to subsequently 100 plaster, the inner skin or form may be made removable and expanded metal lathing may replace it. In the case of a floor but one skin or facing, the bottom member, is needed to receive and hold the concrete, and a finishing coating of cement or other material 105 may be added.

In floor construction it is evident that the metal employed should be of somewhat 110 heavier gage than that for walls, with the flanges and holes larger and the reinforcing rods proportionately heavier.

By the arrangement herein disclosed, the reinforcing rods extending through the holes in the flanges causes the rods to be brought 115 close to the bottom of the concrete slab, where it is most desirable to place the reinforcement, while the holes permit the concrete to flow together and join on both sides of the flanges with the result that the slab 120 is not weakened by the ribs or flanges extending partly through it. The flanges form reinforcing ribs extending in one direction with the reinforcing rods extending in the opposite direction.

In using this invention for floor construction, it will be found most valuable for the construction of floors for buildings, bridges, piers, platforms, the rust-proofing of the metal facing peculiarly adapting it for the 125

purposes mentioned. The holes or perforations in the flanges may be made of any shape.

In Figures 8 and 9 there is shown a form 5 of wall construction similar in some respects to Figures 3 and 7, Figure 8 illustrating an upright wall formed of inner and outer skins D and E, respectively, which are similar to the skins A and B shown in Figure 7 10 and other figures of the drawings. The skins D and E may be made up of troughs having flanges 2 with matching perforations 4^a formed with burrs 9, by means of which the facing flanges are anchored together, as in the structure shown in Figure 15 3. The perforations 4^a receive reinforcing rods 5, as in other forms of the invention.

In Figure 8 and associated figures, provision is made for the application of plaster 20 or stucco, or both, respectively, on opposite walls. To prepare the walls D and E and the ceiling F, as shown in Figure 8, for the application of plaster, the metal skin is punched through on numerous elongated 25 lines producing perforations 10 with closely adjacent but separate flanges 11 or 12, the latter being indicated in Figure 10. In Figures 8, 9 and 11 the flanges 11 are oppositely curved with respect to each other to form 30 hooks 13 by the return of the flanges upon themselves, thus providing anchors to receive and retain a surface coating 14 of plaster or the like, permitting use of an interior wall filling 15, which in cheap 35 constructions may be composed of clay but in the case of floors may consist of concrete or the like.

The slots 10 and struck-out flanges 11 or 40 12 are each of considerable length and are arranged more or less parallel with each other and in relatively close relation, and serve to very sensibly stiffen the metal skin, thus materially aiding in strengthening the walls. The slots and flanges bordering them 45 act after the manner of metallic lathing and firmly retain plaster applied to the inner surface of the walls while the metallic lathing on the exterior of the walls serves to receive and hold stucco thereby greatly enhancing the appearance of the exterior finish 50 of the building without material addition to the cost, wherefore the arrangement is particularly advantageous where it is desirable to produce buildings of small initial 55 cost but with an appearance equaling that of more expensive constructions.

The plaster can be put directly upon the 60 perforated skin either before or after the filling-in process, but preferably after. Furthermore, when the metallic skin is embedded in the wall with concrete on one face and plaster on the other, little or no rust-proofing of the metal is needed, for the construction excludes the access of air to the 65 metal and rusting does not occur.

The construction made up of metal skins, steel reinforcements, concrete and plaster is a most desirable construction for buildings up to any size or height and such construction is also available for the production of 70 cheaper buildings now in demand.

A cottage can be built permanently at a low price by using a metal skin for the walls plastered on the inside and stuccoed on the outside and filled with clay of a thickness 75 which will be cool in summer and warm in the winter, while the ceilings of such buildings can be made permanent and fire-proof by using a metal form such as hereinbefore described, that is, by using a metal form plastered on the underside and filled with clay on the upper side. Moreover, the floors may be made with a metal form having steel reinforcements and filled with concrete.

For purposes of brevity, the word "wall" 80 is employed in the claims to include a ceiling, floor, partition or inside or outside wall of any building structure.

What is claimed is:—

1. In building construction, the combination 90 of elongated sheet-metal trough-like elements having longitudinal angle flanges at the edges meeting face to face, fastening means securing the flanges of the elements together, where meeting, to form a continuous wall-facing, with said flanges having matching perforations in alignment, and reinforcing rods smaller in diameter than the perforations and traversing said perforations, said elements being adapted to receive a filling-in-material, embedding the rods and flanges and passing through the 95 perforations and filling the spaces between said flanges.

2. In building construction, the combination 100 of a facing composed of elongated metal sheets with the long edges projecting from the sheets at an angle to provide flanges, and the flanges being associated and held in face-to-face engagement, said flanges having matching perforations, reinforcing rods of materially smaller diameter than the perforations and traversing the aligned perforations, means for securing the metal sheets together, and a flowable and 105 subsequently hardening filling for the wall, embedding the said flanges and the reinforcing rods and also extending through said matching perforations to provide effective continuity of the wall filling.

3. In building construction, the combination 110 of sheet-metal sections with angle flanges at the long edges, said flanges being provided with matching perforations and secured together, reinforcing rods extending through the perforations of said flanges, with the perforations of greater diameter than the rods, said rods being substantially 115 parallel with the faces of the sections and a filling of material embedding the rods and 120

- flanges and initially flowable and subsequently hardening and setting, to spontaneously pass through the perforations to thereby join the sheet metal and filling material together and connect the rods to said material.
4. In building construction, the combination of sheet-metal sections, with angle flanges at the long edges, said flanges being provided with matching perforations and secured together, reinforcing rods extending through the flanges, with the perforations of materially greater diameter than the rods, and a filling of material embedding the rods and flanges and initially flowable and subsequently hardening and setting to spontaneously pass through the perforations to join the metal and filling material together and connecting the rods to said material, said wall also comprising joined metallic units on both faces with the junction means in the form of metallic bars, and reinforcing bars located between the facing means and embedded in the filling means.
5. In building construction, a sheet metal trough-like unit with edge flanges projecting at an angle to the plane of the main portion of the unit, said flanges being in face-to-face contact, and means for connecting the trough-like units together, consisting of matching perforations in said flanges having burrs formed about the edges of the perforations of one flange and projecting through the perforations of the other flange and returned upon and upset against said other flange to connect the two flanges firmly together in the manner of a tubular rivet, said connecting means not obstructing the passage of filling-in material through said perforations, and said perforations being adapted to receive reinforcing rods.
6. In building construction, a sheet metal trough-like unit with edge flanges projecting at an angle to the plane of the main portion of the unit, said flanges having perforations which are alined when the units are assembled with the flanges in face-to-face contact, said perforations being adapted to receive reinforcing rods, and tubular rivets uniting adjacent units together at the perforations, said rivets being formed integral with one flange and engaging the other flange.
7. In building construction, the combination of a sheet metal casing composed of joined trough-shaped units defining the outer skin of a wall, with joined flanges connecting the units, the interior of the wall being filled with an initially flowable mixture of a character to harden while in the wall, said metallic skin having slots punched therethrough and forming outstanding flanges on opposite sides of the slots to receive and hold a coating of initially flowable and subsequently hardening material to produce a finish to the wall, the flanges on the opposite sides of the slots being returned upon themselves and the metallic skin to provide anchoring hooks for the outer coating.
8. In building construction, the combination of a sheet-metal wall facing composed of joined trough-shaped units defining the outer skin of the wall, having joining flanges connecting the units, with one face of each unit provided with punched through elongated slots having curved free edges bent away from each other and returned toward the facing to form outstanding hook-shaped locking edges, a coating of wall-finishing material applied to the outstanding edges of the slots and the corresponding face of the metallic skin, a filling of initially flowable and subsequently hardening material within the wall, said inner and outer coatings embedding the sheet-metal to protect it against rust.
9. In building construction, an exterior metallic casing composed of opposite skins formed of trough-like sections having in-turned flanges provided with perforations, said sections being fitted together with the flanges in face-to-face contact and the perforations alining, rods passed through the perforations in the flanges and being of a length to connect two or more sections, and a plastic filling poured between the sections of the opposite skins.
10. In building construction, the combination of elongated sheet metal trough-like sections having longitudinal angle flanges at the edges, said sections being fitted together with the flanges in face-to-face contact, said flanges having matching perforations in alinement, and transverse rods passed through the perforations and spaced from the body of the sections, said sections being adapted to receive a filling-in material which embeds the rods and flanges and fills in the spaces between said flanges.
11. In building construction, an exterior metallic casing composed of opposite skins formed of trough-like sections having in-turned flanges provided with perforations, said sections being fitted together with the flanges in face-to-face contact and the perforations alining, rods of materially less diameter than and passing through the perforations in the flanges so that the rods occupy the bottom walls of the perforations, and a plastic filling poured between the sections of the opposite skins.
12. In building construction, a metallic casing composed of opposite skins formed of trough-like sections or units having in-turned flanges provided with perforations, said sections or units being fitted together with the flanges in face-to-face contact, reinforcing rods passed through the perforations to receive and hold a coating of initially flowable and subsequently hardening material to produce a finish to the wall, the flanges on the opposite sides of the slots being returned upon themselves and the metallic skin to provide anchoring hooks for the outer coating.

tions and connecting the sections or units at one side, spacing means for joining the units at opposite sides and holding them apart, other reinforcing bars supported by said spacing means, and a plastic filling poured between the sections of the opposite skins.

13. In building construction, a metallic casing composed of opposite skins formed of trough-like sections or units having in-turned flanges, reinforcing bars connecting the sections or units at one side and supported by said flanges, spacing means for joining the sections or units at opposite sides and holding them apart, and other reinforcing bars supported by said spacing means between the opposite skins, and a plastic filling poured between the sections

of the opposite skins and embedding the flanges, the two sets of reinforcing bars and the spacing means.

14. A concrete structure, including an exterior metallic casing composed of opposite skins comprising box-like sections having upturned flanges provided with openings, said sections being fitted together and simulating wall blocks, interconnecting tie rods engaging the openings in the flanges and holding the sections together, and a plastic filling poured between the sections of the opposite skins.

In testimony that I claim the foregoing as my own, I have hereto affixed my signature.

WILLIAM LEWIS EVANS, JR.
